UNITED STATES PATENT OFFICE.

WILSON BROWN AND JOSEPH B. MEADOR, OF MOUNDS, OKLAHOMA.

VALVE.

1,217,700.

Specification of Letters Patent. Patented Feb. 27, 1917.

Application filed March 9, 1915. Serial No. 13,274.

To all whom it may concern:

Be it known that we, WILSON BROWN and JOSEPH B. MEADOR, citizens of the United States, residing at Mounds, in the county of Creek and State of Oklahoma, have invented 5 certain new and useful Improvements in Valves; and we do hereby declare the following to be a full, clear, and exact description of the invention, such as will enable 10 others skilled in the art to which it appertains to make and use the same.

This invention relates to valves, and the primary object of the invention is to provide 15 a valve which embodies a multiple set of outlets which are adapted for alternate communication with the inlets.

Another object of this invention is to provide 20 a valve structure as specified, which embodies a valve casing having an inlet opening positioned adjacent the lower end thereof, a rotatable valve core positioned interiorly of the valve casing and having an opening extending longitudinally therethrough, which has communication with a 25 transversely extending opening provided for communication with the inlets, and a second transversely extending opening provided for communication with any one of the multiple outlet openings, and further to 30 provide means for holding the valve core in adjusted positions, for preventing the accidental rotation of the core, and also for facilitating the proper positioning of the core for providing communication between 35 the inlet and any one of the multiple outlets.

From the foregoing and other objects in view this invention consists in such novel features of construction, combination and 40 arrangement of parts as will be hereinafter more fully described, illustrated in the accompanying drawings and claimed.

In describing the invention in detail reference will be had to the accompanying 45 drawings wherein like characters designate like or corresponding parts throughout the several views, and in which:

Figure 1 is a top plan view of the improved valve,

Fig. 2 is a vertical sectional view through 50 the valve,

Fig. 3 is a cross sectional view on the line 3-3 of Fig. 1.

Referring more particularly to the drawings, 55 1 designates a valve casing, which is

comparatively heavy in construction, and is provided with a central vertically extending bore 2 formed therein, which bore is greater in diameter at the upper terminal thereof, than at the lower terminal. The bore 2 has 60 a rotatable core 3 mounted therein, which fits snugly against the inner wall of the bore 2, and has an upstanding lug 4 formed upon its upper end. The lug 4 projects above the top of the casing 1, and has a lever 5 connected thereto, by means of a bolt 6, whereby the valve core 3 may be rotated by the horizontal oscillatory movement of the lever 5.

A gasket 7 is mounted upon the upper end 70 of the valve casing 1 and is held in place by a washer 8, through which washer extend stud bolts or other analogous fastening devices 9, for holding the disk and the gasket in secure fluidtight engagement with the 75 upper end of the valve casing.

The washer 8 has an upstanding projection 10 formed upon one section thereof, which projection is provided with a plurality of notches 11 formed in the upper edges thereof. The notches 11 are provided for receiving the lower end 12 of a catch lever 13. The catch lever 13 is pivotally connected to the lever 5, by means of an upstanding yoke 14, and it has a helical spring 15 positioned 80 between the under surface of the handle end thereof, and the upper surface of the lever 5, for holding the catch lever 13 in a notch engaging position. The valve casing 1 is provided with a transversely extending 85 opening 16 formed in one side thereof, a short distance upwardly from the bottom of the casing, which opening has communication with an inlet pipe 17. The casing 1 is also provided with a plurality of horizontally disposed radially extending openings 18 formed therein, a short distance downwardly from the upper end of the casing, and diametrically opposite to the opening 16. The openings 18 communicate with outlet pipes 19, each opening communicating with a separate pipe, as is clearly shown in Fig. 3 of the drawings.

The core 3 is provided with a longitudinally extending opening 20, and transversely 105 extending openings 21 and 22, which communicate with the upper and lower ends of the opening 20. The opening 21 is provided for communication with the opening 16, while the opening 22 is provided for com- 110

munication with any one of the openings 18, for permitting of the passage of fluid from the inlet pipe 17 into and through the valve into any one of the outlet pipes 19, this being 5 regulated by the positioning of the valve core 3 and the operation of the lever 5.

The notches 11 which are formed in the upstanding projection 10, correspond with the various openings 18, so that when the 10 lever 5 is moved into any one of the notches 11, the passageway between the inlet pipe 17 and the pipe 19 corresponding to the position of the lever is open, and a communication is established between the pipes 19 and 15 17 to permit of the flow of the liquid therethrough.

In the drawings, three ducts or openings 18 have been shown, but it is to be understood that any desired number of ducts may 20 be employed, without departing from the spirit of this invention.

From the foregoing description taken in connection with the accompanying drawings the advantages of construction and of 25 the method of operation of the improved valve will be readily apparent to those skilled in the art to which this invention appertains and, while in the foregoing description, the principle of the operation of this 30 invention has been described together with various features of construction, it is to be understood that certain minor features of construction, combination and arrangement of parts may be altered to suit practical conditions provided such alterations are comprehended within the scope of what is 35 claimed.

What is claimed is:—

In a valve structure, a valve casing having 40 a valve chamber provided with a tapering

valve seat, said casing having an inlet opening extending transversely through the wall thereof and communicating at its inner end with the chamber, said casing also having a plurality of, radially arranged outlet openings 45 extending transversely through the wall at points from opposite the inlet opening, said outlet openings located near the upper end of the casing and the inlet near the lower end thereof, a tapered valve having a reduced upper end rotatably seated in 50 said chamber and having a longitudinally extending passage centrally therein, said valve being provided with transversely extending passages communicating at their inner ends with the upper and lower ends of said longitudinal passage respectively, their outer ends communicating respectively with the inlet opening and any one of the radially arranged outlet openings, a lever secured at one end to the reduced end of said valve for rotating the same, for registering the transverse passages with the inlet and any one of the outlet openings, a disk carried by said casing and surrounding said 55 valve, an upstanding projection formed on said disk and provided with notches in its upper face, a catch lever carried by the first named lever, said catch lever adapted to engage the notches in the projection to hold 60 said valve in any desired position and against accidental rotation.

In testimony whereof we affix our signatures in presence of two witnesses.

WILSON BROWN.
JOSEPH B. MEADOR.
